GROSVENOR M. CROSS AND RODERIC M. CROSS, OF MINNEAPOLIS, MINNESOTA

SPRING-REACTION NEUTRALIZER

Application filed November 17, 1927. Serial No. 233,975.

- This invention relates to an improved device or mechanism adapted for use generally to neutralize the reaction of springs or yieldable elements such, for example, as are used in the construction of automobiles, to cushion the loads carried thereby, the purpose of thus neutralizing the reaction of the springs being to prevent shocks and jolts from being transmitted to the body of the vehicle.
- 10 An object of this invention is to provide a device adapted to be connected between two elements separated or connected by a yielding means such, for example, as a spring, the device being so constructed that it will allow freedom of initial movement of the yielding means in either direction from a normal or neutral position, that is, the construction of the device is such that it will offer substantially no resistance to the further separation, 15 or the bringing closer together of the two movable elements, no matter from what cause the elements are moved; and while the elements are returning towards their normal or neutral positions, the device will tend to oppose this return movement with a force which is at all points in the return movement, substantially equal to the difference between the normal pressure or tension of the yielding means and its pressure or tension due to its 20 deflection from normal, that is, the opposing force may be so adjusted as to be substantially equal at all times, to the amount by which its pressure or tension is greater or less than its normal pressure or tension, when 25 the elements are in their normal relative positions.

A further object is to provide a hydraulic spring reaction neutralizer adapted to be connected between the frame members of a vehicle chassis and the axles thereof, said neutralizer being so designed and constructed as to substantially counteract the reactive forces of the usual springs interposed between the chassis frame and the vehicle axles, that 30 is, when the springs are either compressed or expanded, as a result of the vehicle passing over a bump or a depression in the road-way, the neutralizer will act against the return of the springs to their normal positions, and 35 will neutralize such movement with the re-

sult that when the wheels encounter a bump or depression in the road-way, practically no jolts or shocks will be transmitted to the vehicle body.

A further object is to provide a device for opposing the reactive forces stored in the vehicle spring as a result of its movement in either direction from a normal position, which comprises a mechanism adapted to be actuated by movement of the springs from a normal position, to cause an opposing force to be temporarily stored in the device, which acts to oppose the reactive forces temporarily stored in the vehicle spring; and the opposing force being greater at large and lesser at small deflections of the springs from normal, and the mechanism being so constructed that the opposing forces temporarily stored therein to counteract the reaction of the springs, may be adjusted to obtain the desired degree of opposition to the reactive forces of the springs when returning to normal positions, which will cause the travel of the body to follow substantially a straight line; that is, the line of travel of the body will not be noticeably affected by the wheels encountering bumps or depressions in the road surface.

A further object of the invention is to provide a spring neutralizer comprising a casing adapted to be secured preferably to the side frame of the vehicle chassis, and having a rock shaft mounted therein to one end of which a lever is connected, which lever has a connection with the vehicle axle, and a spring-actuated plunger being mounted within said casing for circulating the fluid therein, said plunger having a cam-shaped head adapted to be engaged by an arm secured to the rock shaft, the arm being so positioned upon the rock shaft that when the vehicle spring is in neutral position, the plunger will be depressed against a coiled compression spring which constantly tends to urge the plunger upwardly so that when the arm is oscillated in either direction from normal, by compression or expansion of the vehicle springs, the plunger will be moved in a direction towards the rock shaft, thereby causing the fluid to flow into the lower portion of the casing through a valved opening;

and when the arm commences its return movement, as a result of the reaction of the vehicle spring, the plunger will be forced downwardly against the fluid confined in the lower portion of the casing, forcing the fluid beneath the plunger through a series of small ducts normally closed by an annular valve seated under heavy spring tension, the tension of this spring being such that the mechanism will substantially neutralize the reactive forces of the vehicle spring in its return movement; means also being provided for adjustment of the tension of this latter spring.

Other objects of the invention are to provide a spring reaction neutralizing device or mechanism adapted to counteract the reactive forces of the vehicle spring when returning to normal from either direction; to provide such a device of the hydraulic type comprising a plunger adapted to be operated by a cam device, when the movable elements are moved in either direction from a normal position; to provide such a device comprising a plunger-and-valve mechanism adapted to control circulation of a fluid therein, said valve mechanism permitting substantially free circulation of the fluid in one direction, but restricting the return flow of fluid in the opposite direction; to provide anti-friction means for engaging the cam surfaces of the plunger to minimize friction; and, to provide such a device of comparatively simple and inexpensive construction which will be substantially fool-proof and positive in performance and may be manufactured at a minimum cost.

The particular object of the invention, therefore, is to provide a spring reaction neutralizer, more particularly adapted for use in connection with vehicle springs for neutralizing the reactive forces stored therein when in a position other than normal.

Other objects of the invention will appear from the following description and accompanying drawings and will be pointed out in the annexed claims.

In the accompanying drawings, there has been disclosed a structure designed to carry out the various objects of the invention, but it is to be understood that the invention is not confined to the exact features shown as various changes may be made within the scope of the claims which follow.

In the accompanying drawings forming part of this specification:

Figure 1 is a side elevational view of a portion of a motor vehicle showing the improved neutralizer mounted thereon;

Figure 2 is a vertical sectional view, partially in elevation, showing the parts in normal or neutral position;

Figure 3 is a vertical sectional view on the line 3-3 of Figure 5, showing in full and dotted lines the positions assumed by the

rocker arm and plunger, when the vehicle spring is respectively compressed and expanded, the arrows in the lower portion of the figure indicating the flow of fluid upon movement of the plunger in a direction towards the rock shaft;

Figure 4 is a detailed sectional view of the lower portion of Figure 3, the arrows indicating the flow of the fluid when the plunger is returning to normal against fluid pressure;

Figure 5 is an elevational view of the device partially broken away to more clearly show the connection between the rocker arm and the plunger;

Figure 6 is a plan view of the adjusting nut provided for varying the tension in the neutralizing spring; and

Figure 7 is a perspective view of the spring member provided for closing the annular check valve controlling fluid flow into the lower portion of the casing.

The novel spring reaction neutralizing device featured in this invention includes a casing comprising upper and lower sections 2 and 3, respectively, the lower section 3 being secured to the upper section by means of a flanged nut 4, received in threaded engagement with the upper section 2 and having an inwardly turned flange 5 engaged with an outwardly turned flange 6, provided upon the upper edge of the lower section 3. An auxiliary fluid reservoir 7 may be provided in the upper portion of the casing as shown in Figure 5. This reservoir has a demountable cap 8 which may be removed to permit the introduction of fluid, such as oil, into the casing. In operation, the casing is filled with fluid as indicated in Figure 3.

A rock shaft 9 is mounted in bushings 11 and 12, seated respectively in bores 13 and 14 as shown in Figure 5. A suitable packing 16 is interposed between one end of the bushing 12 and a nut 15 to prevent leakage of oil around the shaft 9. A lever 17 is mounted upon the rock shaft 9 and is prevented from rotation thereon by means of splines 18. A lock screw 20 secures the lever 17 to the shaft. The inner end of the rock shaft 9 is preferably smaller in diameter than that portion thereof which traverses the packing nut 15. Axial movement of the rock shaft is prevented as a result of the hub of the lever 17 engaging one end of the bushing 11, the other end of which is seated against the bottom of the bore 13 as shown in Figure 5. A spacing collar 21 has one end seated against the opposite side of the lever 17 and its other end against a shoulder 19, provided in the casing member 2.

An arm 22 is terminally secured to the rock shaft 9, exteriorly of the casing, and preferably has a ball-and-socket joint 23, of ordinary construction, connecting it to one end of a connecting rod 24, the lower end of which is suitably connected to the axle of the vehicle

or to the non-flexing portion of the vehicle spring 25. Figure 1 illustrates a manner of securing the device to the vehicle and, as here shown, the upper portion 2 of the casing is secured to the front hanger 26 of the vehicle chassis by means of bolts 27. Thus, when the spring 25 flexes, as a result of the wheel passing over irregularities in the road surface, the arm 22 will be oscillated to rock 10 the shaft 9.

An important feature of this invention resides in the construction of the means provided for controlling the circulation of the fluid within the casing, each time the arm 22 is oscillated, as a result of the spring 25 being expanded or compressed. Such means consists of a plunger 28 reciprocally mounted in a cylinder 29, and preferably having an enlarged flanged head 31 received in threaded 20 engagement with the lower portion of the casing member 3, as shown in Figures 2 and 3. The cylinder 29 is open at each end. The plunger 28 has a bore 32 adapted to receive a compression spring 33, the upper end of 25 which is seated against the bottom of the bore 32 and its lower end against the bottom of the casing member 3. This spring constantly urges the plunger upwardly.

The plunger 28 has a forked head 34 provided with cam faces 35, one of which is constantly engaged with one end of a stud 36 adapted to roll thereon. This stud is rotatably mounted in a suitable anti-friction bearing 37 mounted in the lever 17. The 30 stud 36 has a reduced central portion 38, tightly fitted in the bore of the roller bearing 37. The opposite end of the stud 36 is reduced in diameter to receive a sleeve 39, secured to the stud by means of a nut 41, terminally mounted upon the reduced portion 35 to the inner race of the roller bearing so that the enlarged end of the stud and also the sleeve 39 may roll upon the cam faces 35, when the lever 17 is oscillated. The diameters of the enlarged end of the stud 36 and 45 the sleeve 39 are identical. The swinging end of the lever 17 is received in the slot 42 provided in the head of the plunger, between the two cam faces 35. (See Figure 5.)

The valve mechanism employed in this 50 novel neutralizer is best shown in Figures 2, 3, and 4. By reference to Figure 3, it will be noted that the interior of the casing is divided substantially into two chambers, an upper chamber 40, and a lower chamber 43. The lower chamber 43 is defined by the bottom wall of the casing member 3, and the lower ends of the cylinder 29 and plunger 28. The upper chamber 40 is defined by the walls of the lower casing member 3, the 55 exterior of the cylinder 29 and the upper

portion of the plunger 28. In Figure 2, the lever 17 and plunger 28 are shown in normal positions, or in the positions assumed when the vehicle spring 25 is in normal or neutral position. When the vehicle 70 spring is compressed, the arm 22 will be moved upwardly to cause the lever 17 to assume substantially the position shown in full lines in Figures 3, wherein it will be noted that the compression spring 33 has caused by 75 the plunger 28 to be moved upwardly, thereby causing fluid to circulate from the upper chamber 40 into the smaller chamber 43.

The valve mechanism provided for controlling the circulation of the fluid between the two chambers consists of an annular ring 44, mounted in the lower portion of the member 3 of the casing beneath the head 31 of the cylinder 29; and a sleeve 45 movably mounted upon the exterior of the cylinder as shown. 80 A series of fluid ducts 54 are provided in the cylinder head 31 adapted to establish communication between the two chambers. These ducts are normally closed by the ring valve 44, yieldably held in closed position by 85 means of a spring member 46, shown in Figure 7. A similar series of fluid ports 47 are also provided in the cylinder head 31, and these are preferably arranged in a circle closer to the bore of the cylinder and positioned to have their upper ends closed by 90 means of the lower end of the sleeve valve 45, as shown in Figure 3. The upper discharge ends of the ports 47 communicate with an annular groove 50, provided in the cylinder head 31. This annular groove is adapted to be closed by the lower end of the valve sleeve 45 as shown. An annular flange 48 is provided on the sleeve 45 against which one 95 end of a comparatively heavy compression spring 49 is seated. The other end of this spring is seated against an adjusting nut 51, received in threaded engagement with the upper end of the cylinder 29 and having a key 52 engaged therewith and with the bore provided in the lower portion of the upper casing member 2, as shown in Figure 2. The key 52 prevents the adjusting nut 51 from relatively rotating with respect to the casing member 2. To adjust the tension of the 100 spring 49, the flanged nut 4 is loosened, after which the lower casing member 3 may be relatively rotated with respect to the upper casing member 2, thereby causing the cylinder to 105 be relatively rotated within the nut 51, with the result that the distance between the flange 48 and the lower face of the packing nut 51 is varied, thus changing the tension of the spring 49. A drain plug 53 is preferably provided in the bottom of the casing member 110 2. Two tension springs 49 are preferably employed. These are concentric and of the same diameter and are arranged with their coils alternating. The upper terminals 55 of the two springs are preferably bent up-

115

120

125

130

wardly and seated in apertures 56 provided in the nut 51. The nut 51 also has its periphery notched as shown in Figure 6 to provide fluid-circulating passages.

5.

Operation

In operation, the entire device is filled with a fluid such as oil, the auxiliary oil chamber 7 being supplied with fluid as desired, to take care of expansion or contraction of the fluid, due to temperature changes. A vent 57 is provided in the cap 8 defining the upper wall of the chamber 7.

- When the vehicle wheel engages an irregularity or a bump in the road-way, causing the vehicle spring to compress, the arm 22 will be oscillated from the full line position shown in Figure 2 to the full line position shown in Figure 3, thereby rocking the shaft 9 and causing the lever 17 to be moved from the position shown in Figure 2 to the full line position shown in Figure 3. Such movement of the lever 17 permits the compression spring 33 to move the plunger upwardly, the cam faces 35 keeping in contact with the head of the stud 36 and the sleeve 39. As the plunger 24 rises, a slight vacuum occurs in the chamber 43, and atmospheric pressure forces the fluid in the upper chamber through the ducts 54 and into the chamber, the valve ring 44 being unseated, as shown in Figure 3, by the pressure of the fluid acting thereagainst. Thus, the lower chamber 43 will be kept full of fluid regardless of the movement of the plunger 28. It is obvious that the action above described, offers no impedance to the movement of the vehicle axle under the body so long as it continues towards the body; that is, as the two movable elements, in this instance, the vehicle axle and the chassis frame members, are moved towards each other from their normal positions, the device offers no impedance to that movement. As the wheel drops beneath the body or into a depression in the road surface, the action is similar, the lever 17, however, swinging to the dotted line position shown in Figure 3. The movement of the arm 22 will also be in the opposite direction, as indicated by the dotted lines in Figure 3. When the parts are thus positioned, it will be noted that the stud 36 and sleeve 39 will be in contact with the cam faces 35 at points on the other side of the vertical. Thus, it will be seen that the free travel of the plunger 28 will be in the same direction or upwardly, regardless of whether the lever 17 is moved from normal to the full or the dotted line positions shown in Figure 3. It will be noted that the device will permit the movable elements such, for example, as the vehicle chassis and the axle, across which it is connected, to be moved in either direction away from normal position, that is, it permits a free initial deflection of the yield-

ing connection from its original degree of deflection.

When the parts have reached the positions indicated in full lines in Figure 3, the excessive pressure or reactive force present in the vehicle spring resulting from its compressed condition, tends to return the vehicle axle to its normal position, thereby exerting a force against the outer end of the arm 22 tending to move it downwardly from the full line position shown in Figure 3 to the full line position shown in Figure 2. In order to move in this direction, it is obvious that the plunger 28 must be forced downwardly as a result of the stud 36 and sleeve 39 acting against the cam faces 35, as the lever 17 returns to its normal position, shown in Figure 2. Such downward movement of the plunger 28 will cause the latter to force the fluid into the chamber 40, causing the sleeve valve 45 to be opened against the pressure of the spring 49, thus permitting fluid to flow from the lower into the upper chamber, as indicated by the arrows in Figure 4. The force necessary to force the plunger 28 downwardly, is exerted by the stud 36 and sleeve 39 against the cam faces 35, and hence must be exerted between body and axle. It is obvious, therefore, that this force opposes the return movement of the body and axle to their normal relative positions.

The action of the plunger and valve mechanism, when the arm 22 is moved from the dotted line position shown in Figure 3 to the full line position shown in Figure 2, is practically identical to its action or operation, when the arm 22 moves from the full line position shown in Figure 3 to its normal position. This will readily be seen when it is understood that the return movement of the arm 22 from either of the positions shown in Figure 3, to its normal position shown in Figure 2, cannot be effected without forcing the plunger downwardly, which movement is opposed by the action of the spring 49 tending to retain the sleeve valve 45 in closed position. A back pressure is exerted against the return movement of the arm 22 in either direction, through the cam faces 35, stud 36 and sleeve 39; lever 22, lever 17, shaft 9, and the connection 24 between body and axle; thereby opposing their return movement to normal relative positions. Hence, the device will, when connected between two relatively movable members connected by a yielding connection, allow free initial movement of said members in either direction from a normal position, either closer together or farther apart; and, conversely, it will also oppose the return movements of said movable members towards their normal positions from either direction.

The magnitude of the force opposing the return movement of the movable elements, such as vehicle body and axle, at any given

point, is determined by the following factors; the lengths of the arm 22 and the connection 24, and the angles at which they are operated from their connection with the vehicle axle; the diameters of the head of the stud 36 and the sleeve 39; the shapes of the cam faces 35; the effective areas of the plunger and the valve sleeve 45, and the pressure of the spring 49. For the purpose of explanation, it will be assumed that all of these are constant with the exception of the cam faces 35 and the size of the spring 49.

The shapes of the cam faces 35 substantially determine the ratio of successive increments of the opposing force to successive increments of deflection of the vehicle spring, whereas, the pressure of the spring 49 will determine the exact amount of the opposing pressure; that is, the ratio of the amount of vertical travel of the plunger during an elementary unit of travel of the axle beneath the body, to the amount of that axle travel, determines the mechanical advantage or leverage of the plunger over the axle during that amount of travel. In other words, the cam faces 35 act as a variable leverage factor between the plunger 28 and the vehicle axle. Thus, almost any relationship of leverages from point to point can be obtained by simply varying the shapes of the cam faces 35. The pressure of the spring 49 together with the effective areas of the sleeve valve 45 and the plunger 28 determine the upward force of the plunger; and this force multiplied by whatever leverage the piston has over the axle at any given point of travel, determines the exact value of the opposing force exerted by the neutralizer between body and axle.

Thus, by properly designing or shaping the cam faces 35, and properly proportioning the lever 17 and arm 22, with a constant velocity of initial axle rise beneath the body, the plunger can be made to travel with uniformly accelerated motion; that is, from zero velocity at its lowest point to maximum at its highest, thereby giving an even change of leverage between the plunger and the axle, the leverage being at all times proportional to the degree of deflection of the vehicle spring, and therefore to the amount by which the pressure of the spring is greater or less than normal. Hence, if the upward force on the plunger is sufficient exactly to oppose the amount by which the vehicle spring is greater or less than normal at any one point, it will be so at all other points, as the leverage of the plunger on the axle changes with the force desired.

As a result of the adjusting nut 51 being mounted for relative vertical movement within the casing, the tension of the spring 49 may be varied to give the desired pressure, that is, its tension may be adjusted so that it will oppose the return movement of the plunger with such force that the apparatus,

as a whole, will oppose the return movement of the vehicle spring with a force at all points substantially equal to the difference between the normal pressure of the vehicle spring and its pressure at these points due to deflection. 70

When it is desired to attach the neutralizer between two movable members having a yielding connection between them whose pressure is not directly proportional to the degree of its deflection, the cam faces 35 may be changed or altered to fit the new conditions and to give always the proper leverages. If it is desired to oppose with pressures not equal to but proportional to the amount by which the pressure of the yielding means is greater or less than normal, the cam faces will remain unchanged, it being only necessary to change the pressure factors acting on the plunger, namely, the tension of the springs 49, together with the fluid areas involved. To obtain other desired forces, the shapes of the cam faces 35 will be altered to fit the particular case. It is obvious that any downward curve of these cam faces, or even a horizontal flat surface, will produce forces at the axle greater at large deflections of the spring and lesser at small. The other forces attainable by varying the shapes of the cam faces 35, are only limited by the curvature of the head of the stud 36 and the sleeve 39, which will not allow too great a sudden change of angle, and the various other simple mechanical factors involved. 90

From the foregoing, therefore, it will be seen that the construction of this novel spring reaction neutralizer is such that it may be readily adapted for use in connection with two movable elements having a yielding connection between them, to substantially oppose the reactive forces stored up in such yielding connection after deflection and when tending to return to normal position, or it may be made to give opposing forces not neutralizing but of almost any value desired. 100

We claim as our invention:

1. A device for opposing the reactive force in a spring element connecting together two relatively movable members, comprising a casing adapted to be secured to one of said members, a rock shaft in said casing having an operative connection with the other of said members, fluid chambers in said casing, an inelastic fluid therein, a valve mechanism between said chambers, a plunger for circulating the fluid between the chambers, a head on said plunger having an off-set portion, and means on the rock shaft adapted to engage said off-set portion and depress the plunger when said shaft is rocked. 115

2. A device for opposing the reactive force in a spring element connecting together two relatively movable members, comprising a casing adapted to be secured to one of said members, a rock shaft in said casing having

an operative connection with the other of said members, fluid chambers in said casing, an inelastic fluid therein, a valve mechanism between said chambers, a plunger for circulating the fluid between the chambers, a head on said plunger having an off-set portion, and means secured to said rock shaft and adapted for swinging movement on a line substantially at right angles to the axis of said plunger and being adapted to engage the off-set portion on the plunger head, said off-set portion causing the plunger to be depressed farther when said plunger-actuating means is at one end of its movement than when said means is at the opposite end of its movement.

3. A device for opposing the reactive force in a spring element connecting together two relatively movable members, comprising a casing adapted to be secured to one of said members, a rock shaft in said casing having an operative connection with the other of said members, fluid chambers in said casing, an inelastic fluid therein, a valve mechanism between said chambers, a plunger for circulating the fluid between the chambers, a head on said plunger having an off-set portion at one end thereof and means on said rock shaft mounted for swinging movement and adapted to engage said off-set portion when said means is positioned at one side of the plunger, whereby the plunger will be depressed a greater distance than when said actuating means is positioned at the opposite side of the plunger axis; said valve mechanism being adapted to restrict the flow of fluid, in one direction, whereby the force required to return the plunger to normal position, will oppose the reactive force stored in said spring element.

4. A device for neutralizing the reactive force in a spring element connecting together two relatively movable members, comprising a casing adapted to be secured to one of said members, a rock shaft in said casing having an operative connection with the other of said members, fluid chambers in said casing, an inelastic fluid therein, a valve mechanism between said chambers, a spring-actuated plunger for circulating the fluid between the chambers, said plunger having a cam-shaped head provided with an off-set portion, and means on said rock shaft engageable with said head to cause said plunger to be actuated when said shaft is rocked, the off-set portion on the plunger head causing the plunger to be depressed a greater distance when said plunger-actuating means is at one end of its movement than when said means is at the end of its movement, whereby the operation of said device may be controlled.

5. A device for neutralizing the reactive force in a spring element connecting together two relatively movable members, comprising a casing adapted to be secured to one of said

members, a rock shaft in said casing having an operative connection with the other of said members, fluid chambers in said casing, an inelastic fluid therein, a valve mechanism between said chambers, a spring-actuated plunger for circulating the fluid between the chambers, said plunger having a cam-shaped head provided with an off-set portion, and means on said rock shaft engageable with said head to cause said plunger to be actuated when said shaft is rocked, said valve mechanism permitting free movement of said plunger from normal position and restricting its return movement, and the off-set portion on the plunger head causing the plunger to be depressed a greater distance when said plunger-actuating means is at one end of its movement than when said means is at the other end of its movement, and whereby the operation of the device may be controlled.

6. A device for opposing the reactive force in a spring element connecting together two relatively movable members, comprising a casing adapted to be secured to one of said members, a rock shaft in said casing having an operative connection with the other of said members, fluid chambers in said casing, an inelastic fluid therein, a valve mechanism between said chambers, a cylinder in the casing open at both ends, a spring-actuated plunger operable in said cylinder and constantly tending to move in a direction towards said rock shaft, the ends of said plunger being adapted to project beyond the ends of the cylinder, means on said rock shaft engageable with the plunger to control its movement, said valve mechanism being adapted to restrict the flow of fluid to retard the return movement of the plunger, and means for adjusting said valve mechanism.

7. A device for opposing the reactive force in a spring element connecting together two relatively movable members, comprising a casing adapted to be secured to one of said members, a rock shaft in said casing having an operative connection with the other of said members, fluid chambers in said casing, an inelastic fluid therein, a valve mechanism between said chambers, a cylinder in the casing open at both ends, a spring-actuated plunger operable in said cylinder and constantly tending to move in a direction towards said rock shaft, the ends of said plunger being adapted to project beyond the ends of the cylinder, means on said rock shaft engageable with the plunger to control its movement, said valve mechanism being adapted to restrict the flow of fluid to retard the return movement of the plunger, and means exteriorly of said device for adjusting said valve mechanism, to vary the force required to return said plunger to normal position.

8. A device for opposing the reactive force in a spring element connecting together two

relatively movable members, comprising a casing adapted to be secured to one of said members, a rock shaft in said casing having an operative connection with the other of said elements, fluid chambers in said casing, an inelastic fluid therein, a normally closed spring-actuated valve mechanism between said chambers adapted to restrict fluid flow in one direction, a cylinder in said casing, a plunger operable in said cylinder for circulating the fluid between said chambers, means constantly urging said plunger in a direction towards said rock shaft, an irregularly shaped cam on one end of the plunger, means on said rock shaft engageable with said cam to cause actuation of said plunger, when said members are moved towards and away from each other, and a portion of said casing being relatively movable to adjust the operation of said valve mechanism.

9. A device for neutralizing the reactive force in a spring element connecting together two relatively movable members, comprising a casing adapted to be secured to one of said members, a rock shaft in said casing having an operative connection with the other of said members, a cylinder having an annular flange received in threaded engagement with said casing, said flange dividing the casing into two chambers, an inelastic fluid in said chambers, a series of ports in said flange, a valve normally closing said ports, a plunger operable in said cylinder for circulating the fluid between said chambers, means constantly urging said plunger in a direction towards said rock shaft, a cam on one end of the plunger engageable with means on said rock shaft, and the cylinder-supporting portion of said casing being adapted for relative rotation to effect adjustment of said valve mechanism, whereby the force required to return said plunger to normal position, will neutralize the reactive force stored in said spring element.

10. In combination with a vehicle including body and axle members having a yielding connection between them, a casing adapted to be secured to one of said members, said casing comprising an upper relatively fixed section and a lower section adjustably secured thereto, a rock shaft in said upper section having an operative connection with the other of said movable members, a cylinder mounted in the lower casing section and having an annular flange suitably secured thereto, a plunger operable in said cylinder and cooperating with said cylinder flange to divide the casing into two chambers, an inelastic fluid therein, a high pressure valve sleeve slidably mounted upon said cylinder and having one end of a spring engaged therewith, an adjusting ring received in threaded engagement with one end of the cylinder and slidably and non-rotatably connected with the upper casing section, means on said rock shaft engage-

able with one end of the plunger to return the latter to normal position, upon return movement of said movable members from abnormal positions, and said lower casing section being adapted for rotative movement to relatively adjust said adjusting ring upon the cylinder to vary the tension of said valve spring, whereby the circulation of the fluid in one direction may be controlled to cause the force required to return said plunger to normal position, to substantially neutralize the reactive force stored in said spring element.

11. In combination with a vehicle including body and axle members having a yielding connection between them, a device adapted to resist return movement of said members after deflection away from a normal relative position, said device comprising a casing adapted to be secured to one of said members, a rock shaft in said casing having an operative connection with the other of said members, fluid chambers in said casing, an inelastic fluid therein, a valve mechanism between said chambers, a plunger for circulating the fluid between the chambers, means on said rock shaft to cause said plunger to be actuated when said shaft is rocked, and a portion of said casing being relatively movable and connected with said valve mechanism, whereby when said movable portion is relatively moved upon the fixed portion of said casing, said valve mechanism will be adjusted.

In witness whereof, we have hereunto set our hands this 12th day of November, 1927.
